WALL CONSTRUCTION

Samuel F. Cox and Percy E. Knudsen, Pittsburgh,
Pa., assignors to Pittsburgh Plate Glass Com-
pany, a corporation of Pennsylvania

Application June 17, 1938, Serial No. 214,246

8 Claims. (Cl. 189—64)

The present invention relates to the mounting of panels in a wall and it has particular relation to the provision of mountings of relatively thin frangible panels such as sheet glass, or the like.

One object of the invention is to provide means for safely supporting panels of glass closing an entire wall, or large opening in a wall, of a building against atmospheric and other forces to which they may be subjected.

A second object of the invention is to provide means of the foregoing type which is simple, attractive and which is not unduly conspicuous from the exterior of a building.

These and other objects of the invention will be apparent from consideration of the following specifications and the appended claims.

The tendency in modern buildings is to increase the amount of light transmitting window space to a maximum and to decrease the amount of space occupied by such opaque, load supporting materials as stone, brick, steel and the like to a minimum. However, it is always necessary to provide a relatively strong massive structure for supporting the superstructure of a building. There is also a definite limit to the size of the sheets of glass which can be manufactured and handled economically and that will withstand atmospheric or other forces in service. For these reasons, it has heretofore been impossible to provide a wall or a large space in a wall which has the appearance of comprising a wall of sheet glass rather than a series of windows set into a supporting wall.

In a wall or a window constructed in accordance with the provisions of the present invention, the foregoing difficulties are obviated by forming the glass into a series of panels, preferably of relatively large dimensions which are secured in sashes that are supported in edge to edge relation with respect to each other by means of a framework of sufficient strength to support the sheets of glass against wind pressure or other forces to which they may be subjected.

The invention involves as a second feature provision of a system of bracing for walls and large windows of glass in which a framework for a series of large panels are supported and braced from within the building, and the glass presents a surface which is substantially free of the pilasters or columns of the building.

As a further feature, the invention involves the provision of a system of slotted or split hollow metallic bars having the edges thereof formed to provide rabbets for the edges of the glass.

For a better understanding of the invention reference may now be had to the accompanying drawings in which like numerals refer to like parts throughout.

In the drawings

Figure 1 is a front or exterior view of a wall or a large window constructed in accordance with the provisions of the present invention.

Figure 2 is a fragmentary cross-sectional view of the construction shown in Figure 1.

Figures 3, 4, 5, 6 and 7 are fragmentary cross-sectional views taken respectively substantially upon the lines III—III, IV—IV, V—V, VI—VI and VII—VII of Figure 1.

Figure 8 is a fragmentary cross-sectional view taken substantially upon the line VIII—VIII of Figure 4.

Figure 9 is a fragmentary front elevational view showing the intersection of certain bars of the framework shown in Figure 1.

In the form of the invention disclosed, a building wall 10 is formed with a rear section 11 and a forwardly offset section 12 that is connected to the rear section by means of intermediate portions 13. As shown in Figure 6 an opening 14 formed in the wall has a frame 15 of metal, such as steel, disposed therein. This frame, at the sides, comprises members 18 preferably of T cross-sectional outline and consisting of a web 19 and rearwardly disposed transverse flanges 21. The outer of the flanges is secured to or embedded in the masonry of wall 12.

The exposed portions of the flange 19 and a portion of the web 21 are enclosed by sections of a housing 22, that includes a flange 24, which is secured to the web by means of screws or bolts 25. It also includes side portions 26, 27 and 28, the forward edge of the latter of which projects forwardly of flange 21, and have inwardly bent portions 29, which at their edges contact with the web 19. Side 28 is also secured by means of rivets 30 to the edge of the flange.

A sash bar 31 of a sash frame preferably, approximately of L shape is disposed in the angle between the flange 29 and the web 19 and includes a base strip or branch 32 having a flange 33, the latter of which engages the outer edge of said web. Backing strip 34 of member 31 engages the forward face of flange 29 and is provided with a groove 35 within which is disposed a member 36 roughly of tubular form and comprising a thin sheet of resilient metal that constitutes a resilient seal or bead against which the rear face of a plate of glass 37 is pressed. The plate is forced against the bead by means of a 55

section spring clip 38 preferably approximately of L shaped cross-sectional contour, having a clamping strip or branch 39, the marginal portion of which is bent to provide a hook 42, the 5 back of which engages the forward face of the glass. A screw 43 extending through branch 39 of resilient member 38 and branch 34 of member 31 and threaded into side 29 of member 22 respectively, presses the first mentioned branch 10 against the glass and the second mentioned flange against the flange 29.

Flange 34 is also provided with an outwardly extending rib 46 disposed in spaced relation with respect to the branch 32 and branch 39 along its 15 inner edge is provided with a rearwardly and then reflexly forwardly bent portion that forms a rib 47 that is disposed between rib 46 and the adjacent face of the leg 32 of member 31. The reflexly forwardly bent portion of rib 47 forms 20 the second branch or leg 48 of the member 38 and the edge thereof is provided with a bead 49.

The marginal portion of the glass plate 37, together with the member 38 is enclosed or concealed by means of a finishing or closure strip 51 25 which is roughly arcuate in cross-sectional contour and at one edge is provided with a curved rib 52 designed to hook over and engage the hooked portion 42 of clip 38. The adjacent edge of the strip is disposed in contact with the outer 30 face of the glass plate 37. The other margin of the strip is provided with a wedge-like bead 53 that hooks under bead 49 to clamp the finishing strip in position.

The bottom portion of the frame 15 as best 35 shown in Figure 7 comprises a plate 60 constituting a sill or a ledge. Upon the ledge is disposed sections of a housing 61 having a rear side wall 62, a top 63 and a forward side 64. The latter terminates in a forwardly extending flange 40 66 resting upon plate 60. Within the angle between the side 64 and the flange 66 is disposed a sash structure 67 corresponding to that already described in connection with Figure 6.

The upper portion of the frame 15 as shown 45 in Figure 5 comprises an angle member 70 which is secured by welding or by other convenient means to the lintel 71 of the building structure. The angle bar 70 and lintel 71 are substantially enclosed by housing sections 72 which include 50 rear sides 73 having horizontal rearwardly extending flanges 74 that rest upon the horizontal web 77 of the angle 70 and are secured to the web 77 by means of rivets or screws 78. Of course, the flange may, also, be secured by welding 55 or by any other convenient means. The top portions 79 of the housing extend under the vertical flange 81 of the angle 70 and at their forward edges are provided with two vertically upwardly extending portions 82 and 83 which are 60 interconnected by horizontal ledges 84 to provide an angle within which is disposed the upper bar 86 of the sash frame. Reference again may be had to Figure 6 for a complete understanding of this frame. Plate 87 provides a closure between the upper edge of portion 83 and the lower 65 edge of the masonry 88 constituting a part of the building wall.

As shown in Figure 3, means for supporting 70 the edges of the panels of glass intermediately of the two side frames comprise vertical members 91, similar to members 18 shown in Figure 6 and comprising a web 92 having rear flanges 93. The vertical members 91 are braced by members comprising horizontal rearwardly extending tubes 75 95 having flanges 96 upon the extremities there-

of secured to the flanges 93, by means of bolts 98. At their rear extremities, the tubes are secured to columns 99 (shown in Fig. 2), which may be load supporting elements of the building.

A housing 105 is disposed about the flanges 93 5 preferably is of rectangular cross-section and the sides 106 thereof are secured to the edges of the flanges 93 by means of screws or rivets 107. At its forward edge or side the housing is slotted as indicated at 108 to receive the web 92 of the 10 vertical member 91. Portions 110 of the forward face of the housing provide shoulders upon opposite sides of the web 92 against which is seated a bar 111 of the sash frame. This bar is identical in cross-section to those previously 15 described.

Housings 105 are formed in sections corresponding in length approximately to the height of the sheets of glass 37. The extremities of the housing are spaced to receive and support the 20 extremities of tubular horizontal bars 112. These bars are so notched at their extremities as indicated at 113 as to fit about the flanges 93 of the vertical members 91, and thus to prevent 25 horizontal displacement.

As best shown in Figure 4, bar 112 comprises 30 sheet metal bent into the form of a rectangular tube having side walls 116 and a rear wall 117. The forward portions of the walls 116 are inwardly bent to provide the forward wall 118. The two inwardly bent portions meet along the median plane of the hollow cross-bar and the marginal portions 119 thereof are outwardly bent to provide a rib 121. Sash frames 122 are disposed in the angles between the flange 121 and 35 the forward wall 118 of the horizontal bars. This frame corresponds to and constitutes a portion of the frame already described in connection with Figure 6. As shown in Figure 8, the extremities of the walls 117 are semicircularly 40 notched to fit about braces 95.

As shown in Figures 1 and 9, the corners of the various panels are secured and concealed by means of rosette plates 125 which are held in position by means of screws 126, threaded into 45 the forward edges of the webs 92.

The mode of assembly of a wall structural construction constituting the subject matter of the present invention is practically self-evident from the foregoing descriptions. It will be assumed 50 that the masonry of the building has already been constructed and that the side frames 118 and the housing 23 therefore have been placed in position. The plate 60 and the housings 62 likewise should be assembled. The vertical 55 members 91 are then stood in place and the lower extremities thereof are secured by welding or by other convenient means to the bottom plate or sill. As each section of the casings is slid into position, the horizontal bars 112 are slipped into 60 position with the extremities thereof resting upon the upper end of the sections 105 and with the slotted portions 113 fitting about the flanges 93 in such manner as securely to lock the horizontal bars from displacement. Additional sections 105 can then be slid over the supports 91 and in this manner the assembly is continued 65 until completed. The ends of the vertical bars are secured to the framework of the buildings after the housings 105 and bars 112 have been 70 mounted. Sections of housings 22, 61 and 72 are then secured in position. It will be noted that the outer extremities of the end bars 112 are disposed between the ends of sections 61, while the ends of uprights 91 are disposed be- 75

tween the ends of sections 61 and 79. Assembly of the framework for the glass and the mounting of the panels of glass follows conventional procedure and need not be described in detail. 5 Finally the rosette plates 125 are secured in place over the corners of the plates.

In accordance with the provision of the present invention, the sheets or units of glass 37 may be of practically any dimension commensurate 10 with ease of handling and adequate mechanical strength. The amount of framework and building wall disposed between the different units in the completed structure is so small that a wall composed of such units present the appearance of 15 a practically continuous wall or window of glass. At the same time, the glass is adequately reinforced by the framework against wind pressures and any mechanical stresses which are likely to be imposed thereupon. The vertical members of 20 the framework are designed primarily for supporting and reinforcing the panels of glass. However, they are of great rigidity and may be employed as load carrying columns in the building.

25 The construction may be employed in the formation of substantially continuous walls of sheet glass. It is also possible to employ the construction in the assembling of very large windows.

Although only the preferred embodiment of 30 the invention has been described and shown in the foregoing specifications, it will be apparent to those skilled in the art that numerous modifications may be made therein without departure from the spirit of the invention or the scope of 35 the appended claims.

What we claim is:

1. A building comprising a transparent wall composed of a plurality of panels of glass supported by a framework which comprises vertical 40 members having rearwardly disposed transverse flanges and forwardly extending webs, the vertical members being secured at their opposite ends to the framework of a building, sheets of glass disposed transversely upon opposite sides of the webs, a plurality of the sheets of glass being disposed in vertically superposed relation with respect to each other, a plurality of tubular sections corresponding in length to the widths of the superposed sheets of glass, the tubular sections being 45 slotted to receive the webs of the vertical members, horizontal members disposed between the vertical members and comprising tubes having flanges along their forward edges disposed between the contiguous horizontal edges of adjacent sheets of glass, the ends of the horizontal members being secured between and supported upon the contiguous ends of the tubular sections.

2. A construction as defined in claim 1 comprising columns disposed in rearwardly displaced relation with respect to the glass panels and horizontal braces interconnecting the vertical members and the columns at the points of intersection between the vertical members and the horizontal members.

3. A construction as defined in claim 1 in which the ends of the horizontal members are

notched to receive the flanges of the vertical members.

4. A construction as defined in claim 1 in which the horizontal members are slotted and the edges are forwardly bent in superposed relation to provide the ribs. 5

5. A transparent wall composed of a plurality of panels of glass supported by a framework, which includes vertical members of metal having transversely-disposed rearward flanges and forwardly-extending webs, the vertical members being secured at their opposite ends to the framework of a building, sheets of glass disposed transversely upon opposite sides of the webs, the flanges being enclosed by tubular members longitudinally slotted to receive the web portions of the vertical members and providing backings for the sheets of glass. 10

6. A transparent wall composed of a plurality of panels of glass supported by a framework, which includes vertical members of metal having transversely-disposed rearward flanges and forwardly-extending webs, the vertical members being secured at their opposite ends to the framework of a building, sheets of glass disposed transversely upon opposite sides of the webs, the flanges of the vertical members being enclosed by tubular members longitudinally slotted to receive the web portions of the vertical members, said tubular members providing backing means 30 for the sheets of glass and being cut into sections, horizontal members disposed between the upper and lower edges of adjacent sheets of glass and having their ends supported between contiguous ends of the sections of the tubular members. 35

7. A transparent wall composed of a plurality of panels of glass supported by a framework, which includes vertical members of metal having transversely-disposed rearward flanges and forwardly-extending webs, the vertical members being secured at their opposite ends to the framework of a building, sheets of glass disposed transversely upon opposite sides of the webs, tubes of rectangular cross-section disposed about the flanges of the vertical members and being slotted 45 along their forward faces to receive the webs of the vertical members, said faces providing backings for the edges of the sheets of glass.

8. A transparent wall composed of a plurality of panels of glass supported by a framework, which includes vertical members of metal having transversely-disposed rearward flanges and forwardly-extending webs, the vertical members being secured at their opposite ends to the framework of a building, sheets of glass disposed transversely upon opposite sides of the webs, tubular members of rectangular cross-section disposed about the flanges of the vertical members and being slotted along their forward faces to receive the webs of the vertical members, the sides of the 60 tubular members being secured to the edges of the flanges of the vertical members, and the forwardly facing portions of the tubular members providing backings for the sheets. 65
